BIRD CAGE

James B. Gresham, New York, N. Y.

Application May 12, 1949, Serial No. 2,610

Term of patent 14 years

(Cl. D31—2)

To all whom it may concern:

Be it known that I, James B. Gresham, a citizen of the United States of America, residing in the Borough of Manhattan, city, county, and State of New York, have invented a new, original, and ornamental Design for a Bird Cage, of which the following is a specification, reference being had to the accompanying drawings, forming part thereof, wherein:

Figure 1 is a front elevation of a bird cage embodying my new design.

Fig. 2 is a side elevational view of the bird cage shown in Figure 1.

The dominant feature of my design resides in the configuration of the bird cage in the form of a cat seated on its haunches.

I claim:

The ornamental design for a bird cage, as shown and described.

JAMES B. GRESHAM.
